UNITED STATES PATENT OFFICE.

GUSTAF OSKAR PETERSSON, OF DALSBRUK, RUSSIA.

FURNACE OR KILN FOR ROASTING ORES.

SPECIFICATION forming part of Letters Patent No. 781,904, dated February 7, 1905.

Application filed December 7, 1903. Serial No. 184,241.

To all whom it may concern:

Be it known that I, GUSTAF OSKAR PETERSSON, a subject of the King of Sweden and Norway, and a resident of Dalsbruk, in the county of Abo, in the Grand Duchy of Finland, Russia, have invented certain new and useful Improvements in Furnaces or Kilns for Roasting Finely-Crushed Ore, Burning Dolomite, &c., of which the following is a specification.

The present furnace or kiln, illustrated in the accompanying drawings in a longitudinal section in Figure 1, in a cross-section in Fig. 2, and in plan view in Fig. 3, consists, essentially, of a shaft *a*, contracted at the bottom and traversed by a number of arches *b c d* at different levels, said arches, however cross-wise, not extending across the entire shaft, but being arranged alternately at both sides of it, as best seen from Fig. 2. The space beneath the bottom arch or bottom arches *b* at one end communicates with the outer air through passages *e*, arranged in one of the abutment-walls of the arch, while the other end of said space is connected with a gas-fire chamber and a chamber *f*, arranged beside the latter in the other abutment-wall. The gas is supplied to the fire-chamber through a pipe *g*. The space beneath the arches *c*, situated above the arches *b*, communicates at one end with the chamber *f* and at the other with a chamber *h*, arranged in the opposite abutment-wall and communicating at its upper part with one end of the space beneath the arches *d*, which space at the other end communicates with a chamber *i*, arranged above the chamber *f* and connecting with the chimney *k*, which should preferably be carried through the gas-supply pipe *g*, so as to admit of heating the gas. The air used for the combustion of the gas will thus be heated by the material to be roasted in the lower part of the furnace or kiln as the air passes to the chamber *f*, and the products of combustion formed in said chamber subsequently flow back and forth through the material to be roasted on their way to the chimney. By using several arches and several chambers in the walls of the

furnace or kiln it is evidently possible to compel the gases to pass several times back and forth through the material to be treated. The capacity of the furnace or kiln evidently can be increased either by making it higher and using a greater number of arches *b c d* above one another than is shown in the drawings or by making it wider and placing several arches side by side or by both these arrangements simultaneously. A good result may also be obtained by using only one arch *b c d*, since by making these arches very large the furnace or kiln may be made quite efficient, while it is at the same time easy to manage on account of the few arches. The material to be roasted is fed in at the top either intermittently or continuously and is taken out at the bottom orifice of the shaft. Part of it will then in the beginning stop on the arches and remain there; but between the arches a passage will always be formed, through which the remainder of the material successively descends, according as the final product is drawn off below, and this latter part will be acted upon by the traversing current of gas.

In the walls of the kiln sight and slice holes should be arranged so that the material to be roasted can be reached in case it should clog. Such holes should likewise be arranged in the end walls of the kiln opposite the apertures beneath the arches *c* and *d*.

Having now particularly described and ascertained the nature of my said invention and in what manner the same is to be performed, I declare that what I claim is—

An improved furnace or kiln for roasting finely-crushed ore, burning dolomite, &c., provided with flat arches *b, c, d* arranged in a shaft at different levels zigzag with reference to one another, and having a space between themselves and the walls of the shaft and with the space beneath the bottom arch or arches *b* communicating at one end with the outer air and at the other end with a fire-chamber which in its turn communicates with one end of the space beneath the arch or arches *c* above, while the other end of the latter space is in com-

munication with a chamber h , in its turn communicating with the space beneath the top arch or arches d , said space last mentioned communicating with a chimney either directly or through the aid of other arches compelling the gases to flow repeatedly back and forth in the furnace or kiln.

In witness whereof I have hereunto set my hand in presence of two witnesses.

GUSTAF OSKAR PETERSSON.
